Application April 28, 1934, Serial No. 722,845

6 Claims. (Cl. 179—171)

The present invention relates to resistance-capacity or impedance coupled amplifiers for amplifying signals in a relatively wide frequency band.

5 The invention relates particularly to resistance-capacity coupling networks for amplifiers wherein the signal may vary in frequency between relatively wide audio frequency limits, such, for example, as from 20 cycles to one megacycle.

10 As is well known and understood, an amplifier of the above type includes one or more interstage coupling networks comprising an output or plate coupling resistor, an input or grid coupling resistor, and a coupling condenser. A coupling network of that character may be employed, for example, between two amplifier stages or between an amplifier stage and an output circuit such as a transmission line.

20 In designing a resistance-capacity coupled amplifier for covering a wide frequency band, the coupling or grid blocking condenser becomes an important factor at both high and low frequency limits.

25 The low frequency portion of the frequency response characteristic of the coupling network, embodying resistance-capacity coupling means, may be improved by increasing the size of the coupling condenser but not without greater increased cost. It is, therefore, an object of the invention to provide means for increasing the low frequency response characteristic of a resistance-capacity coupled amplifier, without increasing the size of the coupling condenser.

30 It is a further object of the present invention to provide an improved coupling network for an electric discharge amplifier system embodying resistance-capacity coupling means which may have an improved overall frequency response characteristic and high gain.

35 The invention will, however, be better understood from the following description when considered in connection with the accompanying drawing and its scope will be pointed out in the appended claims.

In the drawing,—

40 Figure 1 is a schematic circuit diagram of an electric discharge amplifier provided with an interstage coupling network embodying the invention;

45 Fig. 2 is a simplified equivalent circuit diagram of the amplifier shown in Figure 1 whereby the design and operation thereof may better be understood;

50 Fig. 3 is a vector diagram of voltages existing

in the coupling network shown in Figs. 1 and 2; Fig. 4 is a curve diagram showing the effect of the coupling network of Figs. 1 and 2 upon a resistance-capacity coupling network; and—

5 Fig. 5 is a schematic circuit diagram of an amplifier showing a further embodiment of the invention.

Referring to Figure 1, 10 and 11 are electric discharge amplifier devices or tubes of the high mu type in an amplifier having input terminals 12 and output terminals 13 and an interstage coupling network 14. The first stage amplifier device 10 is of the screen grid or other high gain type comprising a control grid 15, a cathode 16, a screen grid 17 and an output anode 18. 15 The control grid 15 is coupled to one of the input terminals 12 through a coupling condenser 19 and is provided with a grid resistor 20 connected to ground 21 through a filter impedance 22. The cathode 16 is provided with a self-bias resistor 23 also connected to ground. A bypass condenser 24 is provided for the filter impedance 22 to cathode, thereby completing the input circuit of the first stage device.

The screen grid is supplied with positive potential from any suitable source (not shown) 25 through a supply lead 25 and the output anode 18 is likewise connected to a positive source of anode potential through an output circuit 26 in which is connected an output or anode coupling resistor 27 and a filter impedance or resistor 28. The filter resistor 28 is provided with a bypass condenser 29 connected to ground as indicated, thereby completing the output circuit of the first stage device 10.

35 The second stage amplifier device 11 is likewise preferably of the high gain type and is provided with a cathode 30, a control grid 31, a screen grid 32, and an output anode 33, connected through an output circuit lead 34 to one of the 40 output terminals 13, the other of which is connected with a positive potential supply lead 35 as indicated.

45 The input circuit for the second stage amplifier device 11 comprises an input grid lead 36 and a grid or input coupling resistor 37, terminating with a ground connection to cathode as indicated. Negative biasing potential is applied to the grid 31 through the resistor 37 from any suitable source such as the resistor 38 in the cathode circuit, as shown. The screen grid 32 receives a positive biasing potential through a supply lead 39.

50 The output circuit of the first stage amplifier is coupled to the input circuit of the second stage 55

amplifier through the coupling condenser shown at 40. Signals appearing across the output coupling impedance or resistor 27 are applied to the input coupling resistor 37 through the coupling 5 condenser. For an amplifier designed to cover a wide frequency band, the coupling or grid blocking condenser 40 becomes an important factor in attaining high fidelity particularly at the low frequency limit of the audio frequency range. For 10 a given second stage amplifier device 11, the maximum value of grid resistance 37 or R_g , as it will hereinafter be referred to, is fixed and the product $C_g R_g$ which determines the grid circuit distortion at a given frequency may be increased 15 by increasing the value of C_g , the latter being the capacity of the condenser 40 and hereinafter being referred to as C_g .

However, as the physical dimensions of C_g increase, a point is soon reached where an increase 20 causes an appreciable rise in circuit capacity to ground, which capacity appears in parallel with the parallel resistance R_p or the resistor 27 and R_g , and, for a given combination, determines the high frequency distortion. For a given ground 25 capacity, the high frequency distortion may be reduced only by reducing the parallel resistance value usually by reducing R_p . This not only reduces the gain from the first stage amplifier device 10, but necessitates a larger filter condenser 30 29 or C_f as it will hereinafter be referred to. Therefore, it is usually advantageous to maintain C_g as low in value as possible.

It has been determined that the distortion caused by a low product $C_g R_g$ may materially be 35 lessened by utilizing a low filter capacity C_f . In fact, as a limiting case, by making infinite both the filter impedance 28 or R_f , as it will hereinafter be referred to, and the internal plate resistance of the first stage amplifier device 10 or r_p , as it 40 will hereinafter be referred to, the low frequency distortion may be made any value desired and, by making the product $C_g R_g$ equal to $C_f R_p$, may be reduced to zero.

Referring now to Fig. 2, the internal impedance 45 of the first stage amplifier device 10 is indicated at r_p , together with the μe_g or the voltage generated by the tube 10 connected in parallel with the output coupling impedance R_p and the bypass condenser C_f in series, as one branch of the output 50 circuit, the other branch of which is the coupling condenser C_g and the load or grid resistor R_g . The voltage existing across the load impedance or from the plate to ground is indicated as e_1 and the output voltage across the grid resistor R_g is indicated 55 as e_2 . The currents flowing in the two plate or output circuits are indicated as i_1 and i_2 and the voltage drop through the internal tube impedance r_p is equal to the vectorial value of $(i_1+i_2) r_p$. 60 (1) $\mu e_g = e_1 + (i_1+i_2) r_p$ = Voltage generated by the driver tube or first stage tube 10, vectorial values being used throughout.

The voltages e_2 and e_1 will be out of phase with each other as indicated in Fig. 3, by the vector lines representing said voltages, the angle between the voltages being determined by the value of the condenser 40 and other circuit constants. For minimum low frequency distortion, the product $C_g R_g$ must equal $C_f R_p$, when impedances r_p and R_g are relatively high with respect to R_p , and the reactance of C_f . Furthermore, the voltage $i_1 r_p$ should be in phase with the voltage $i_2 r_p$ and the voltage e_2 should be in phase with the voltage 75 $(i_1+i_2) r_p$, as given in Equation (1) above.

For minimum low frequency distortion, the product $C_g R_g$ must equal $C_f R_p$ when impedances r_p and R_g are relatively high with respect to R_p and R_g , for by this means alone may the vector $i_1 r_p$ be made to lie parallel to the vector i_2 . Then, 5 the vector $i_1 r_p$, being parallel to i_2 , it becomes parallel to $i_2 r_p$ (actually parts of the same straight line). The generated voltage μe_g lies at an angle to $i_1 r_p$ and $i_2 r_p$, because of the voltage e_1 (see Equation 1) but, since r_p is specified much larger 10 than R_p , the generated voltage μe_g lies substantially parallel to i_2 and therefore e_2 .

It is obvious that the product $C_g R_g$ will vary with frequency but the product $C_f R_p$ will vary in exactly the same manner so that the products will 15 remain equal. For that reason, the length of the vectors in Fig. 3 will vary with frequency but as they vary in identical manner and quantities, the shape of the vector diagram remains constant. Therefore, the ratio of e_2 to μe_g and the phase 20 angle between the two are independent of frequency, thus fulfilling the requirements for distortionless amplification.

Vectorially adding the voltage, $(i_1+i_2) r_p$, which is substantially parallel with the voltage e_2 , to the 25 voltage e_1 , it will be seen that voltage μe_g will lie substantially parallel, and, therefore, in phase with the voltage e_2 . In other words, the desired condition of operation is obtained when the output voltage e_2 across the coupling network is in 30 phase with the input voltage or voltage generated by the driver tube μe_g . This condition of operation depends upon the relation between the impedance in the branch circuits comprising in the 35 one circuit, the output coupling or plate impedance R_p and the filter condenser C_f , and, in the other branch, the coupling condenser C_g and the input or grid resistor R_g . In the relation, as hereinbefore indicated, and as follows:

$$(2) \quad C_g R_g = R_p C_f \quad 40$$

This equation may be derived from two equations as follows:

Capacitive reactance of condenser C_f =

$$(3) \quad X_1 = \frac{1}{2\pi f C_f} = \frac{1}{K C_f} \quad 45$$

Capacitive reactance of condenser C_g =

$$(4) \quad X_2 = \frac{1}{2\pi f C_g} = \frac{1}{K C_g} \quad 50$$

$$(5) \quad \frac{X_2}{R_p} = \frac{X_1}{R_p} \quad (\text{from vector diagram})$$

This is the requirement for the two impedances which determine the angle of i_1 and i_2 to give 55 i_1 and i_2 parallel in Fig. 3. or—

$$(6) \quad K C_g R_g = K C_f R_p$$

where $K = 2\pi f$

A condition where the current in the two branch 60 circuits are out of phase with each other and out of phase with the output voltage is indicated in the diagram in Fig. 3 by the dotted lines. Under such conditions, it will be seen that the voltage generated by the driver tube 10 resulting therefrom is widely out of phase with the output voltage e_2 thereby causing appreciable distortion. For minimum distortion, therefore, the output voltage across the grid or load impedance must be in 70 phase with the voltage generated by the driver tube, and the currents through the branch circuits of the network must also be in phase with each other and with the input voltage e_g .

With a circuit arranged in accordance with the 75

Equation (2), the coupling condenser 40 may have a minimum capacity while, at the same time, the low frequency response characteristic of the amplifier network may be maintained at a relatively high level, the gain of the low frequency response being indicated in Fig. 4 by the solid line curve 42 as compared with the dotted curve 43 for a normal resistance capacity coupling circuit not including the frequency characteristic correction system shown and described.

It is assumed that r_p and R_f are greater than R_p or R_s . However, this is not a limiting condition. If either of the impedances are less in value, the vector μe_g (Fig. 3) swings more to the right and out of phase with e_2 . This may be corrected for by making C_f still smaller, thus swinging $i_1 r_p$ to the left and bringing μe_g back in phase with e_2 .

The swing to the right observed in μe_g is caused by the apparent change in capacity of C_f if a small R_f is used, or to shortening of the vectors $i_1 r_p$ and $i_2 r_p$ if low r_p is used. In either case, a partial correction may be obtained by reducing C_f , thus swinging the vector μe_g toward its desired position.

In this case the shape of the vector diagram varies in such a manner that maximum distortionless amplification is obtained at the frequency at which the capacity reactance of C_f approaches the resistance R_f .

It will be appreciated that the response characteristic 42 is obtained without increasing the size of the coupling condenser which is employed for obtaining a response characteristic as indicated by the curve 43 and the correction may be applied to any amplifier covering any predetermined frequency range, the zero point of the curves of Fig. 4 being the lower limit of the selected frequency range of operation. As determined by the use of an ordinary condenser as a coupling means in the coupling network, the improvement in the frequency response characteristic is indicated in Fig. 4 by the added ranges A and B, the range B indicating the practical extent of the range to a point of permissible distortion. From an inspection of the curves, it will be seen that a relatively greater improvement in the low frequency response characteristic is obtained without added equipment or cost in providing the interstage coupling network and without impairing the high frequency response characteristic.

Referring to Fig. 5, an output coupling system for an amplifier is shown in connection with a resistance-capacity coupling network for a transmission line.

The amplifier or output stage comprises two parallel connected high impedance electric discharge amplifier devices 45 to which signals are applied through input terminals 46 and a coupled condenser 47 and grid impedance 48. Feed-back preventing resistors 49 are provided in the grid leads and bias potential is applied to the grid input circuits from a suitable source such as a self-bias resistor 50 in the common cathode lead. The return circuits are grounded as indicated. The output circuits of the two amplifier devices 45 are connected in parallel to an output circuit 51 in which is located an output coupling resistor 52 or R_p and a filter impedance 53 or R_s , which, in the present example, is an audio frequency choke coil. In circuit with the impedance R_s is a high frequency choke coil 54 and a current limiting resistor 55. The circuit is connected to a high voltage positive anode supply lead 56 along with a supply lead 57 for the screen electrodes for the devices 45.

An output load circuit 58 is connected across output terminals 59 in turn connected through coupling condenser 60 and condenser 61 across the output coupling impedance R_p .

The output load circuit 58 is provided by a low impedance shielded transmission line which may be of the type known commercially as RCA "Cabley", having relatively low impedance at signal frequencies. The line load may be considered as R_p , while the coupling condenser 60 may be considered as C_g . The condenser 61 is part of one branch circuit with R_p and may be considered as C_f .

With a pair of RCA-247 tubes located at 45 and with an output line 58, having an impedance of 50 ohms, R_p equal to 50 ohms and coupling condenser C_g and filter condenser C_f , each equal to 250 MF a maximum low frequency and high frequency response is obtainable. Without the use of the circuit shown, a coupling condenser at 20 C_g of substantially 750 MF is required together with a lower impedance at R_p . Therefore, it will be seen that a material saving in cost is obtainable, together with an improved frequency characteristic through the use of coupling elements in 25 a resistance-capacity coupling network embodying the invention.

In the present example, the filter choke coil 53 and the plate impedance of the tubes 45 are preferably relatively high as shown and described 30 in the preceding Figs. 1 and 2. Since the operation is the same for the coupling network of Fig. 5 as for the coupling network of Fig. 1, further description is believed to be unnecessary.

I claim as my invention:

1. A resistance-capacity coupling network including in combination an output anode circuit comprising branch circuits, one of said branch circuits including an output anode coupling resistor and a filter condenser in series relation to each other and to the anode circuit, and the other of said branch circuits including a coupling condenser and a load or grid resistor in series relation to each other, the product of the capacity of the coupling condenser and the resistance of the load resistor being substantially equal to the product of the resistance of the first named output coupling resistor and the capacity of filter condenser.

2. In a resistance-capacity coupled amplifier, an interstage coupling network comprising in combination, an output anode resistor, a filter condenser in series therewith, and a second circuit substantially in parallel with said resistor and condenser and comprising a coupling condenser and a coupling resistor, the product of the resistance and capacity values of which are equal to the product of the resistance and capacity values of the first named resistor and condenser.

3. A resistance-capacity coupled amplifier including an electric discharge amplifier device and an output coupling network therefor of the resistance-capacity coupling type, characterized by the fact that the coupling elements including a plate resistor R_p , an output coupling resistor R_g , 60 a coupling condenser C_g , and a filter condenser C_f , are of such related impedance and capacity values that the equation $C_g R_g = R_p C_f$ is substantially satisfied, whereby the output voltage across the output coupling resistor is substantially in phase with the voltage generated by said device connected therewith.

4. An impedance coupled amplifier including a high gain amplifier tube, and an output coupling 75

network therefor of the resistance-capacity coupling type, characterized by the fact that the coupling elements, including an anode circuit impedance device R_p , a filter condenser C_f in series therewith, and a coupling condenser C_g and load impedance R_g in series as a parallel circuit for said first named impedance and condenser, are of such related impedance and capacity values that the equation $C_g R_g = R_p C_f$ is substantially satisfied, whereby the output voltage across the load impedance is substantially in phase with the voltage generated by the amplifier tube connected therewith.

5. In an electric signal amplifier, a coupling network comprising a driver tube, an anode impedance therefor, a filter condenser in series with said impedance to signal currents, a filter impedance, and a coupling condenser and a load impedance connected in series, substantially in parallel with said series connected anode impedance and filter condenser, said coupling elements thereby forming two substantially parallel branch circuits having impedance values such that the product of anode impedance and the capacity of the filter condenser equals the product of the load impedance and the capacity of the coupling condenser, whereby the signal currents through said branch circuits are in phase with each other and in phase with the input voltage generated in 30 said driver tube.

6. The combination with an audio frequency signal transmission line having a relatively low audio frequency impedance, of amplifier means connected therewith to apply audio frequency signals thereto in a low range of audio frequencies 5 without appreciable distortion, said means including a plurality of amplifier tubes having anodes connected in parallel, an anode output impedance connected with said anodes, an anode filter impedance connected in series with said anode output impedance, a bypass capacitor connected between the junction of said impedances and a cathode return connection, a coupling capacitor connected between the anode and one side of said transmission line, and means providing a cathode return connection for the other side of the line, said anode output impedance and bypass capacitor providing a branch circuit from the anode to the cathode connection, and said coupling capacitor and transmission line impedance providing another branch circuit from the anode to the cathode connection, said branch circuits having such impedance values that the product of the anode output impedance and the 25 capacity of the bypass capacitor equals the product of the transmission line impedance and the capacity of the coupling capacitor.

ARTHUR C. STOCKER. 30
